CLAIM

The ornamental design for a universal counter deposit ticket including MICR (magnetic ink character recognition) characters, as shown and described.

DESCRIPTION

FIG. 1 is a top face view of a universal counter deposit ticket including MICR (magnetic ink character recognition) characters showing our new design;

FIG. 2 is a bottom face view thereof;

FIG. 3 is another embodiment of a bottom face view thereof;

FIG. 4 is yet another bottom face view of the embodiment shown in FIGS. 2; and,

FIG. 5 is still another bottom face view of the embodiment shown in FIG. 3.

The broken line showing of the environment is for illustrative purposes only and forms no part of the claimed design.
